UNITED STATES PATENT OFFICE.

RUDOLPH THIEM, OF HAMILTON, OHIO, ASSIGNOR TO THE KENTUCKY STOVE COMPANY, OF LOUISVILLE, KENTUCKY.

DESIGN FOR A COOKING-STOVE.

SPECIFICATION forming part of Design No. 31,095, dated June 27, 1899.

Application filed May 29, 1899. Serial No. 718,749. Term of patent 7 years.

To all whom it may concern:

Be it known that I, RUDOLPH THIEM, a citizen of the United States, residing at Hamilton, Butler county, Ohio, have invented and produced a new and original Design for Cooking-Stoves, of which the following is a specification, reference being had to the accompanying drawing, forming part thereof.

The drawing is a perspective view of a cooking-stove, showing my new design.

As shown in the drawing, the leading or material features of my design consist in the oven-door A, ornamented by a series of non-uniform double-ended foliate volutes disposed 15 non-symmetrically about a central ground or panel; in the fire-door B, also ornamented by a series of non-uniform double-ended foliate volutes non-symmetrically disposed upon the door; in the reservoir end C, also ornamented 20 by a series of non-uniform double-ended foliate volutes non-symmetrically disposed upon the reservoir end; in the oven-hearth D, ornamented by double-ended foliate volutes non-symmetrically disposed and by piercings at the margins of and between some of the 25 volutes; in the skirt or leg-frame E, ornamented by symmetrically-disposed symmetrical double-ended foliate volutes and by lattice-work within and between some of the volutes, and in legs F, ornamented by leaves 30 at their tops and bases and foliate volute scrolls at their sides and double-ended volute fillets above their bases.

Having described my invention, what I claim as new, and desire to secure by Letters 35 Patent, is—

The design for a cooking-stove, as herein shown and described.
